MAGNETO

Kenneth A. Harmon, Longmeadow, Mass., assignor to Wico Electric Company, West Springfield, Mass., a corporation of Massachusetts

Application June 27, 1939, Serial No. 281,385

3 Claims. (Cl. 171—209)

This invention relates to an improved magneto designed for use in signalling systems, such for example as certain telephone systems.

Heretofore, the magnetos used for such systems have been of the wound-armature type which entails the use of slip rings and brushes to conduct the current from the rotating generating coil. These rings and brushes are a source of frequent trouble and it is desired to eliminate them and resort to a type of magneto wherein the generating coil is stationary, and the rotor carries the magnets. This type, however, makes necessary a rotor of larger diameter and this, in turn, necessitates many changes in the construction, mounting, and arrangement of parts.

This invention has for an object to provide a magneto of unwound-rotor type which will be at least no larger than the wound-armature type of magneto and will at least fit within the same space occupied by the wound-armature type of magneto, characterized by provision of a novel form of crank-operated hand drive for the rotor; a novel form of switch actuating means; and other features relating to the construction, mounting and arrangement of parts.

These features will best be understood as the detailed description proceeds.

The invention will be disclosed with reference to the accompanying drawings, in which:

30 Fig. 1 is a sectional elevational view of a magneto involving the invention;

Fig. 2 is a cross sectional view thereof taken on the line 2—2 of Fig. 1;

Fig. 3 is a fragmentary view of a part of the operating handle, looking in a direction at right angles to that in which Fig. 1 was taken;

Fig. 4 is a cross sectional view taken on the line 4—4 of Fig. 1 showing the switch mechanism;

40 Fig. 5 is a sectional plan view taken on the line 5—5 of Fig. 4;

Figs. 6 and 7 are side and front elevational views, respectively, of the cam mechanism for actuating the switch mechanism; and

45 Fig. 8 is a diagrammatical view showing the electrical connections of the apparatus.

Referring to these drawings: the magneto includes an open-topped hollow box-like housing member 10 (Figs. 1 and 2) of molded non-magnetic material which may, for example, be of some suitable plastic material. In the rear wall of this member is fixed a tubular stud 11 which extends horizontally into the interior of the hollow member 10. Also fixed in the same wall is 55 a stud 12 which extends outwardly therefrom

at a level above stud 11. Both studs may be inset into the member 10 during the casting process or fixed thereto in any other suitable way. The front wall of member 10 has an outward tubular extension 13 of approximately square cross section, forming a compartment 14. Connecting this compartment 14 with the interior of the member 10 is an opening 15 of modified cylindrical form. Shoulders 16 are formed at the intersection of the compartment 14 with opening 10 5 15 and seated against these shoulders is a panel 17 of insulating material, fixed to the housing by cap screws 18. The panel has fixed thereto a bushing 19 located coaxially with stud 11 for a purpose to be described. The panel 17 closes 15 the opening 15 except for a narrow slot 20, formed between its upper edge and the top wall of extension 13. A cover 21, held in place by a pin 22 fixed in one side wall of extension 13 and by a screw 23 in the opposite side wall of said 20 extension, closes the outer end of compartment 14. The upper end of member 10 is closed by a cover 25, held in place by cap screws 26, threaded into the upper wall of member 10.

The magneto includes a stator made up of 25 three laminated-iron members (Fig. 2) including two side members 27 and a bridging member 28, mounted in the form of an inverted U. A coil 29 is mounted on the bridging member 28 or core. The side members are secured to member 30 10 by being inset therein during the molding process or in any other suitable way. Each side member consists of a stack of laminations bound initially together by rivets 30 and set into the non-magnetic side walls of member 10. The core 35 28 is also made up of a stack of laminations, bound together by rivets 31. The ends of the core rest one on top of each side member 27 and are held in place by clips 32 and cap screws 33, threaded into the upper ends of members 27. 40 The confronting lower parts of the side members 27 are of concave formation, finished in true coaxial relation with stud 11.

The rotor includes two short but powerful magnets 35 and pole shoes 36 therefor. The 45 shoes 36 are made up of iron laminations, initially bound together by rivets 37. The magnets and shoes are assembled, as shown, with like poles of the magnets interconnected by the shoes, and these parts are then placed in a mold and the 50 latter filled with non-magnetic material 38 which binds the parts together. This part 38 dovetails into each pole shoe and shrinkage of the cast material draws the shoes tightly against the ends of the magnets 35. The material 38 also 55

completely encompasses the magnets 35 and the side faces of the pole shoes 36.

The rotor (Fig. 1) is provided with a central longitudinally-extending bore, coaxially disposed with reference to the curved convex surface of the pole shoes 36. Into one end of this bore is driven a bearing bushing 40 which is rotatably mounted on the exterior of stud 11. Into the other end of this same bore fits a hub 41 which has a flange 42, fixed by screws 43 to one end face of the rotor. The rotor is held against axially-endwise movement in either direction by the engagement of the bushing 40 with the rear wall of member 10 and by the engagement of flange 42 with the inner end face of bushing 19.

The rotor has a drive shaft 45 which is rotatably supported near one end in a bearing bushing 46, fixed in the outer end of the tubular stud 11. The shaft projects beyond the outer end of stud 11 to receive a pinion 47, fixed thereon. The shaft also extends inwardly beyond its bearing 45, through the hollow stud 11, through the hub 41 and bushing 19, terminating with a button 48 of insulating material, located in the compartment 14. The shaft 45 is mounted to slide in an axial direction in the bearing 46, the hub 41 and bushing 19 and it is free to turn in the bearing and bushing. A pin 49, fixed in and passing diametrically through shaft 45, has radially projecting ends which are engaged in slots 50 formed in hub 41, thereby providing a driving connection between the shaft and rotor. Provision is made for a limited amount of relative turning movement between the shaft and hub 41. For example, each slot 50 is made as a portion of a helix, as best shown in Fig. 6. The slots therefore act as cams whereby, if the rotor is held against rotation and shaft 45 is turned in the proper direction, the cam slots 50 acting on pin 49 cause the shaft to move axially to the left until the ends of the pin strike the bottoms of the slots. Thereafter the pin ends will drive the rotor and will remain in the bottoms of slots 50 until the turning effort on shaft 45 is stopped. Then the shaft will move axially to the right under the influence of a spring 52, which is coiled around shaft 45 and acts between a washer 53 (abutting pin 49) and a collar 54 fixed to shaft 45. The engagement of collar 54 with the inner end of bearing 46 limits the outward movement (to the right) of shaft 45. The rotor itself is held against any appreciable axial movement. The rotor also tends to remain in the position shown in Fig. 2 by reason of the powerful pull of the magnets 35 on the stator element. Thus, when shaft 45 is first turned, the rotor remains stationary until the ends of pin 49 have advanced in the cam slots 50 and reached the bottoms thereof, whereupon continued turning of the shaft drives the rotor in unison therewith.

This axial movement of shaft 45 is utilized to actuate a switch which serves to open the talking circuit of a telephone and close a ringing circuit. This switch is, or may be, of the usual and well-known form and the functions it performs in telephone circuits and such circuits themselves are, or may be, of the usual and well-known form. As shown herein, the switch is mounted in the compartment 14 (Figs. 4 and 5) and includes a spring switch arm 56 having on opposite sides thereof near its outer and free end, a pair of contacts 57 and 58. This switch arm plays between two fixed conducting strips 59 and 60, bearing contacts 61 and 62, respectively. The spring in

the arm 56 normally holds contact 57 engaged with contact 61 but, when shaft 45 advances, as it is initially turned, the button 48 moves arm 56 to disengage the contacts 57 and 61 and engage the contacts 58 and 62. The last-named pair of contacts are held engaged for the duration of operation of the magneto.

As shown in Fig. 4, the spring switch arm 56 is connected by a conducting strip 63, fixed to panel 17, to a terminal screw 64. Strip 59, likewise suitably fixed to panel 17, is connected to the terminal screw 23, above described. Strip 60 is fixed, as indicated, to panel 17 and connected thereto by one of the described screws 18 is one terminal wire 65 of coil 29. The other terminal wire 66 of coil 29 is connected by another of the screws 18 to a conducting strip 67, also fixed to panel 17, and having connected thereto a terminal screw 68. The wires 65 and 66 extend through the slot 20, above described.

The conventional talking circuit of the telephone is connected to terminal screws 23 and 64, whereby such circuit is controlled by switch 56, being closed when the magneto is not in operation. When signalling is to be effected, the magneto is operated, whereupon the talking circuit is opened by switch 56 and a ringing or signalling circuit closed thereby, whereby the magneto coil 29 is connected across the terminal screws 64 and 68, the latter being grounded as indicated. Thus, a bell-ringing, alternating-current generated by the magneto, may be transmitted over a circuit which includes a wire connected to terminal screw 64 as one side of the circuit and the ground as the other side of the circuit.

The case of the telephone is shown in part by dotted lines at 69 in Figs. 1 and 4.

For operating the magneto, the usual hand-operated crank is provided. A crank 70 is screw threaded onto the hub of a gear 71 which is rotatably mounted on the stud 12 and meshes with the pinion 47. The gear 71 is held in axial position between a shoulder 72 on the stud and the head of a cap screw 73 threaded into the stud. The crank 70 has a folding handle 74 which is normally held in the position illustrated in Fig. 1 by a spring 75. The handle has a stud 76 which is rotatably mounted in two spaced ears 77 formed on the handle. The spring is coiled around this stud and the ends of the spring are connected one to the crank 70 and one to the stud 76. A pin 78 fixed to stud 76 is adapted by abutment with the left hand side of crank 70 to limit the outward or clockwise movement of the handle. When the handle 74 is released, the spring 75 restores it to the position illustrated in Fig. 1 wherein it is entirely housed in a cylindrical recess 80 in the casing 69.

In operation, rotation of the magnetic rotor is resisted by the magnetic pull which is exerted on the laminated stator. Hence, when the operator turns the crank 70 to drive shaft 45, the rotor does not immediately turn. Rather, in its initial stage of rotation, shaft 45 turns without turning the rotor and this portion of the rotation of the shaft is utilized, through the pin 49 and helical slots 50, to cause an axial movement of the shaft to the left, as viewed in Fig. 1. The rotor, as above described, is held against any substantial axial movement. The switch 56 is thus actuated to open the talking circuit of the telephone apparatus by separating the contacts 57 and 61 and to close the ringing or signalling circuit by engaging the contacts 58 and 62. The 75

shaft, having thus moved the switch, also maintains it in the described position as long as driving torque is applied to shaft 45. After the switch has been thus actuated, the pin 49 engages the inner and closed end of each slot 58 and thereafter the rotor is positively driven from the shaft. When the driving torque on shaft 45 is relaxed, the rotor comes to rest in the illustrated position and the spring 52 moves the shaft 10 to the right into the illustrated position, thus moving the switch 56 back into the illustrated position and closing the talking circuit.

The invention affords a magneto which is somewhat smaller in height and length than the conventional wound-armature type of magneto and which is much more powerful due to the use of the magnets 35 which, although small, are of exceedingly high coercive force. The difficulties, resulting from the use of slip rings and brushes, 20 are overcome by making the coil stationary. The use of a stationary coil and the shortest possible magnetic circuits, makes necessary the elimination of the conventional type of crank shaft and the substitution of a crank-operated gear mounted on a stud outside the housing 10. The circuit closer 56 has to be actuated from the rotor shaft and this is effected in the novel manner above described. One end of the chamber in which the rotor is mounted has been partitioned off by the 25 panel 17 to form a compartment 14 in which the circuit closer and its contacts are housed and protected against dust and dirt as well as mechanical injury.

What I claim is:

1. In a signalling magneto, a laminated stator element, a coil thereon, a magnetic rotor cooperating with said element to establish a magnetic circuit therethrough and vary the flux in such circuit, a frame supporting said element, a hollow stud fixed to said frame and on which said rotor is mounted, means for holding said rotor against any substantial movement axially of said stud, a drive shaft slidably and rotatably mounted in said stud, a driving connection between said 40 shaft and rotor including a pin and helical slot, whereby when the shaft is initially turned the rotor remains stationary momentarily due to the magnetic pull between the rotor and stator and the shaft moves axially as it turns in said slot 45 throughout the confines of said slot, and a switch actuated by the advancing movement of said shaft.

2. In a signalling magneto, a laminated stator element, a coil thereon, a magnetic rotor cooperating with said element to establish a magnetic circuit therethrough and vary the flux in such circuit, a frame supporting said element, a hollow 5 stud fixed to said frame and on the exterior of which said rotor is mounted, means for holding said rotor against any substantial movement axially of said stud, a bearing within said stud near the outer end thereof, a drive shaft rotatably 10 mounted in said bearing and extending entirely through and beyond the inner end of said stud, a hub fixed to the rotor and loosely mounted on said shaft with an end face located adjacent the inner end of said stud, said hub having a helical 15 slot extending from said end face inwardly a short distance, a pin fixed to said shaft and having a part engaged in said slot, resilient means tending to hold the shaft in an axial position 20 wherein the pin lies in the entrance end of said slot, and means for rotating said shaft, whereby since rotation of the rotor is resisted by the magnetic pull on the stator, the shaft initially turns 25 without turning the rotor until said pin engages the inner end of said slot and whereby the shaft moves axially against the force of said resilient means into a second axial position, and a switch in circuit with said coil and actuated by movement of said shaft into said second axial position. 30

3. In a signalling magneto, stationary and movable elements effective on relative movement to produce a change of magnetic flux and cause the generation of an electromotive force, a shaft for driving said movable element, a housing for 35 supporting and enclosing both said elements and including one upstanding wall in which said shaft is supported and an opposed upstanding wall having an opening therethrough leading to one end face of the movable element, a panel fixed in said 40 opening and having an inner face located adjacent said end face of the movable element and partitioning said opening, a switch mounted on the outer face of said panel, a cover closing the outer end of said opening, and means for moving 45 said shaft axially on initial rotation of said movable element, said shaft having a part extending through said panel and operable on axial movement of the shaft to actuate said switch. 50

KENNETH A. HARMON.
